ATTORNEY

UNITED STATES PATENT OFFICE.

JOSEPH E. HAGAN, OF AKRON, OHIO.

TRAIN STOP.

Application filed September 16, 1922. Serial No. 588,669.

To all whom it may concern:

Be it known that I, JOSEPH E. HAGAN, a citizen of the United States, residing at Akron, in the county of Summit and State 5 of Ohio, have invented new and useful Improvements in Train Stops, of which the following is a specification.

This invention relates to automatic train stopping means, the general object of the 10 invention being to provide means for energizing a pair of rails in a block by a train approaching the block and means on the train which are actuated by the train passing over the energized rails for stopping the 15 train.

Another object of the invention is to provide means whereby a towerman can de-energize the rails if he wishes the train to proceed.

20 A still further object of the invention is to provide means whereby the engineer can prevent the operation of the train stopping means and also to return the parts to normal position after the train has been stopped 25 so that he can proceed.

Another object of the invention is to provide means whereby the engineer can operate the train stopping means to make an emergency stop.

30 Another object of the invention is to provide means on each car for bleeding the airline so as to apply the brakes on each car simultaneously with the application of the brakes of a locomotive.

35 A further object of the invention is to provide signal means on the locomotive for warning the engineer that the train is about to be stopped.

This invention also consists in certain 40 other features of construction and in the combination and arrangement of the several parts, to be hereinafter fully described, illustrated in the accompanying drawings and specifically pointed out in the appended claims.

45 In describing my invention in detail, reference will be had to the accompanying drawings wherein like characters denote like or corresponding parts throughout the several views, and in which:—

Figure 1 is a fragmentary view of a locomotive showing one of the roller contacts thereon.

50 Figure 2 is a sectional view through Figure 1,

Figure 3 is a diagrammatic view of the parts on the engine.

Figure 4 is a diagrammatic view of the track parts.

Figure 5 is a diagrammatic view of the 60 train parts.

Figure 6 is a view of one of the contact rails.

Figure 7 is a section on line 7—7 of 65 Figure 4.

Referring to Figure 4, A indicates a block and B a short section of track which is insulated from the rest of the track. A pair of contact rails 1 are arranged in the block, these rails being preferably constructed, as 70 shown in Figure 6 which shows the rail 1 as containing a strip 2 of conducting material which projects above the tread of the rail so as to be engaged by the contact rollers on the train. A tower C, or the 75 like, is arranged adjacent the block and this tower contains the battery 3, the magnet 4, the lamp 5 and the bell 6 which are connected with the battery and with one of the rails of the short block B. The other rail 80 is connected with the battery and with one of the rails 1. The other rail 1 is connected with a lever 7 in the tower which is normally held in raised position by a spring 8 and which is brought into engagement with a 85 contact 9 by the core 10 of the magnet when said magnet is energized. A latch member 11 holds the lever 7 in its lowered position and in engagement with the contact 9, said latch being adapted to be depressed manually 90 so as to release the lever to permit the spring 8 to raise it out of engagement with the contact.

From the above it will be seen that when a train enters the short block B it will complete the circuit to the magnet, lamp and bell, thus notifying the towerman that a train is approaching his block and at the same time bring the lever 7 into engagement with the contact 9 so as to complete the circuit to the rails 1. If the block A is clear 95 and it is proper for the train to proceed, the towerman will depress the latch 11 to permit the spring to raise the lever 7 and thus break the circuit to the rails 1 so that 100 as the train passes over these rails the parts carried thereby will not be affected. However, if it is necessary to stop the train in the block the towerman will not touch the latch 11 so that the rails 1 are left connected 110

with the battery. Thus the train passing over these rails will have its electrically operated parts actuated by the current from battery 3 and the train will be stopped.

5 The contact rollers 12 for engaging the rails 1 are carried in the yoke-shaped ends of the stems 13 which are slidably arranged in the frames 14, carried by the engine. Springs 15, located on the stems and pressing against the collars 16 on said stems tend 10 to hold the rollers in engagement with the contact strips.

The stems are electrically connected with a magnet 17 by the conductors 18, a switch 15 bridging said conductors, said switch including a hand lever 19' which is normally held against the switch contact 19 by a spring 20. By raising this hand lever to open said switch the engineer can prevent the current 20 from battery 3 from affecting the parts on the train. The energizing of magnet 17 will bring lever 21 against contact 22 so as to complete circuit 23 from battery 24 on the train to the magnet 25. This magnet will 25 operate valves 26 and 27 through the connections 28, thus shutting off the steam to the cylinders and applying the brakes to stop the train and at the same time close the switches 29 and 30, switch 29 completing the 30 circuit 31 between the battery 24 and a bell 32, a lamp 33 and a magnet 34 which actuates a valve 35 for supplying steam or compressed air to a whistle 36, these parts acting to warn the engineer that his train is 35 about to stop. The closing of switch 30 completes a circuit 37 from battery 24 to the cars of the train, each car having a magnet 38 thereon which is connected by the conductors 39 with the circuit 37 and said magnet 40 acts upon the valve 40 to bleed the air pipe 41 and thus apply the brakes to the wheels of each car. Each car is provided with sockets 42 which are connected with one end of the circuit wires 37 and with projections 45 which are connected with the other ends of the wires, the projections on one car being adapted to engage the sockets on another car. A resistance 44 and tell tale lamps 45 are connected by the conductors 46 with the circuit 37, these lamps 45 acting to indicate 50 that the circuit is not broken. I provide two or more lamps so that if one should burn out the remaining one will still indicate that the circuit is not broken. The resistance 44 permits but a small amount of current to flow to the lamps 45 so that the parts on the cars will not be affected by this small current. The lever 21 is held in engagement with the contact 22 with the spring 46 compressed by 55 means of the latch 47 which is connected with the core of the magnet 48. This magnet is located in the circuit 49 which is connected with the battery 24 and a switch 50 is located in said circuit, the switch including a hand lever 51 which is normally held in open

position by a spring 52. By closing the switch the engineer can close the circuit of the magnet 48 so as to withdraw the latch 47 and thus release the lever 21 so as to permit the spring 46 to move it away from the contact 22 and thus break the circuit of magnet 25. This will permit the engineer to start his train so that he may proceed.

An emergency lever 53 is located in the cab and this lever is adapted to close a circuit 54 which includes the battery 24 and the magnet 25 so as to actuate valves 26 and 27, thus stopping the train and the movement of this lever 53 will actuate a member 55 which is connected by the conductors 56 to the circuit of the parts 32, 33 and 34, so that when said member 55 is moved by the lever 53 the circuit to said parts will be broken, thus permitting the engineer to actuate the valves 26 and 27 without actuating the alarm means 32, 33 and 34.

From the above it will be seen that a train approaching the block A will close the circuit to the alarm means in the tower to notify the towerman that a train is approaching his block and at the same time will close the circuits to the rails 1 in the block. If it is proper for the train to proceed the towerman will depress the latch 11 to break the circuit to the rails 1. If the train should be stopped in the block the towerman would permit the parts to remain as they are so that as soon as the train reaches the rails 1 the magnet 17 will be energized so as to close the circuit to the magnet 25 and thus apply the brakes, cut off the steam and actuate the alarm means on the engine to notify the engineer that his train is being stopped. At the same time the circuits to the magnets on the cars will be closed to apply the brakes on the cars at the same time that the brakes on the locomotive are applied. If, for any reason, the engineer does not wish his train stopped he may depress the hand lever 19' so as to prevent the track battery from operating the magnet 17. If the train has been stopped and the engineer wishes to proceed to the tower, for instance, he may depress the lever 51 so as to close the circuit to the magnet 48 and thus release the switch 21 and break the circuit to the magnet 25. He can then start his locomotive. If the engineer wishes to make an emergency stop he would move the lever 53 to the left closing the circuit to the magnet 25, thus actuating the valves 26 and 27 and in this movement of the lever the member 55 will be moved to break the circuit to the alarm means in the locomotive so that these will not operate.

It is thought from the foregoing description that the advantages and novel features of my invention will be readily apparent.

I desire it to be understood that I may make changes in the construction and in the combination and arrangement of the several

parts, provided that such changes fall within the scope of the appended claims.

What I claim is:—

1. A train control of the class described comprising electrically operated means upon the train for applying the brakes, shutting off the steam and sounding an alarm, means for closing the circuit to such electrical means from a point along the track and 10 means for closing the circuit to such means in the cab while breaking the circuit to the alarm.
2. A train control of the class described comprising electrically operated means upon 15 the engine for applying the brakes, shutting off the steam and sounding an alarm, electrically operated means upon each car for applying the brakes of each car, such means being electrically connected with 20 those of the engine, means for closing the circuits to such means from a point along the track and an emergency switch in the cab for closing the circuits of such means, while breaking the circuit of the alarm.
- 25 3. A train control of the class described comprising a track having a short block and a long block, contact rails in the long block, a circuit for the contact rails, a magnetic controlled switch therein, latch means for holding the switch in closed position after being closed by the magnetic means and 30 means for actuating the magnetic means when a train enters the short block.
4. A train control of the class described

comprising a track having a short block 35 and a long block, contact rails in the long block, a circuit for the contact rails, a magnetic controlled switch therein, latch means for holding the switch in closed position after being closed by the magnetic means, 40 means for actuating the magnetic means when a train enters the short block, and alarm means adjacent the magnetic switch and located in the circuit thereof.

5. A train control of the class described 45 comprising electrical means upon the train for bleeding the brake line, closing the steam supply and sounding an alarm, a switch for such means, a magnet for closing the switch, electrical means along the 50 track for supplying current to the magnet, means in the cab for preventing the magnet from being energized when desired and manually operated means in the cab for opening the switch.

55 6. A train control of the class described comprising electrical means upon the train for bleeding the brake line, closing the steam supply and sounding an alarm, means for completing the circuit of such electrical 60 means from a point along the track, an emergency lever in the cab for completing the circuit to such means and at the same time breaking the circuit to the alarm means and tell-tale means in the cab for indicating 65 the condition of the circuit.

In testimony whereof I affix my signature.
JOSEPH E. HAGAN.
